DESIGN FOR A HANGER FOR DOLL CLOTHING

Rose M. Borden, New York, N. Y., assignor to Debby Doll Dress Co., Brooklyn, N. Y., a co-partnership consisting of Max A. Borden, Rose
M. Borden, and Dorothy E. Borden

Application January 24, 1941, Serial No. 98,353

Term of patent 14 years

To all whom it may concern:

Be it known that I, Rose M. Borden, a citizen of the United States and a resident of the city, county, and State of New York, have invented a new, original, and ornamental Design for a Hanger for Doll Clothing, of which the following is a specification, reference being had to the accompanying drawing, forming a part thereof, wherein:

Fig. 1 is a front elevation of a hanger for doll clothing, embodying my design; and

Fig. 2 is an end elevation of the same.

I claim:

The ornamental design for a hanger for doll clothing, substantially as shown.

ROSE M. BORDEN.
